UNITED STATES PATENT OFFICE.

WILLIAM ABERCROMBIE DUNN, OF SMITHVILLE, MINNESOTA, ASSIGNOR OF
ONE-HALF TO ATHOL MORTON MILLER, OF DULUTH, MINNESOTA.

ROLLER-MILL.

SPECIFICATION forming part of Letters Patent No. 709,082, dated September 16, 1902.

Application filed January 3, 1902. Serial No. 88,303. (No model.)

To all whom it may concern:

Be it known that I, WILLIAM ABERCROMBIE DUNN, a citizen of the United States, residing at Smithville, in the county of St. Louis and State of Minnesota, have invented certain new and useful Improvements in Roller-Mills; and I do hereby declare the following to be a full, clear, and exact description of the invention, such as will enable others skilled in the art to which it appertains to make and use the same.

This invention relates to improvements in apparatus for rolling metal I-beams, channel-beams, and the like, and contemplates improved means by which the metal acted upon may be conveyed from one part of the apparatus to another in a manner to effect a very large saving of time in operation with a consequent diminution of expense and to greatly increase the capacity.

In apparatus of the kind to which my improvements relate and in the methods at present practiced the metal is conveyed from the shaping-mill to the intermediate mill and thence to the finishing-mill by means of a single conveyer or "table," and inasmuch as the partly-formed beam coming from the shaping-mill has a length such as precludes it being readily passed and repassed through the intermediate and finishing mills it is customary to divide the metal into two or more lengths, one of which is conveyed to the intermediate mill for further reduction, while the other is carried to a reheating-furnace and there kept until the first length has received its final pass, when it is likewise treated.

My invention consists, broadly speaking, of a table interposed between parts of the apparatus—for example, the shaping and the intermediate mills—and an auxiliary table connected by a laterally-arranged conveyer with the first-named table at the point of location of the metal-dividing means and leading to a second intermediate mill, the tables operating to convey the two lengths of metal to the respective mills for simultaneous treatment.

The details of my invention are fully set forth in the following description, and the accompanying drawing illustrates in plan

view an apparatus embodying the improvements in their preferred form.

Referring to the drawing by numerals, 1 denotes a shaping roller-mill, 2 is an intermediate roller-mill, and 3 a table connecting the mills and formed, as is usual, of parallel frames and rollers, the latter being rotated from a source of power. (Not shown.) It will be understood that the table extends in front of the shaping-mill to convey the ingot or slab thereto, and also beyond the intermediate mill to the finishing-mill. (Not shown.) Extending laterally across the table is an endless conveyer 4, consisting of a pair of endless chains or cables 5, passed around sprocket wheels or sheaves 6 and 6', 6" and 6', the latter being driven from a suitable source of power.

7 denote carriers, each supported to move on parallel tracks 8 and connected to one of the chains or cables 5.

9 designates a second or auxiliary table constructed similarly to the table 3 and across which extends the conveyer 4. The table 9 leads to a second intermediate mill 10 and beyond the latter to a second finishing-mill. (Not shown.)

The metal after the final pass through the shaping-mill is conveyed by the table 3 to a point opposite the cutter, which may be a power-driven circular saw 11, mounted on a rocking frame 12, pivoted to a suitable base 13. The metal is divided by the cutter, and the forward length, which is positioned to extend across the conveyer 4, is engaged when the conveyer is set in motion by dogs 14 on the carrier 7 and conveyed to the auxiliary table 9. The tables 3 and 9 are then operated and the lengths carried thereby are simultaneously moved to the respective intermediate mills for further reduction, after which they are conveyed by said tables to the respective finishing-mills. By the provision of the second or auxiliary table and the connecting-conveyer the divided lengths of metal are simultaneously conveyed for further treatment in a sufficiently-heated state, thus obviating the necessity of reheating, which, as stated above, obtains in the processes at present practiced. My improvement, therefore, not only dispenses with the handling of lengths

for reheating, which effects a large saving of time and a consequent diminution of the running expenses, but by the simultaneous further treatment of both lengths the capacity 5 of the apparatus is very largely increased.

I claim as my invention—

- The combination of a metal-carrying table leading from a shaping-mill to an intermediate mill and from thence to a finishing-mill, 10 a second metal-carrying table in parallel relation to the first table and leading to a second intermediate mill and from thence to a second finishing-mill, means for dividing the metal into lengths said means being located

at the first-named table, and an endless conveyor between the tables adapted automatically to transfer a severed portion of the metal to the second table whereby both portions of the metal are conveyed to the intermediate and finishing mills for simultaneous 15 treatment.

In testimony whereof I affix my signature in presence of two witnesses.

WILLIAM ABERCROMBIE DUNN.
